US00D608283S

(12) **United States Design Patent**
Mack

(10) **Patent No.:** **US D608,283 S**
(45) **Date of Patent:** **** Jan. 19, 2010**

(54) **BATTERY**

(75) Inventor: **Robert J. Mack**, Milwaukee, WI (US)

(73) Assignee: **Johnson Controls Technology Company**, Holland, MI (US)

(**) Term: **14 Years**

(21) Appl. No.: **29/327,182**

(22) Filed: **Oct. 31, 2008**

(51) **LOC (9) Cl. 13-02**

(52) **U.S. Cl. D13/119; D13/103**

(58) **Field of Classification Search D13/102-108, D13/110, 118-119, 184; 429/96-100, 163, 429/176**

See application file for complete search history.

CLAIM

The ornamental design for a battery, as shown and described.

DESCRIPTION

FIG. 1 is a top isometric view of the battery according to an exemplary embodiment;

FIG. 2 is a top plan view thereof;

FIG. 3 is a first side elevation view thereof;

FIG. 4 is a second side elevation view thereof;

FIG. 5 is a first end elevation view thereof;

FIG. 6 is a second end elevation view thereof; and,

FIG. 7 is a bottom plan view thereof.

The broken lines shown in FIGS. 1-7 are for illustrative purposes only, and form no part of the claimed design. The dash-dot lines shown in the Figures are for the purpose of illustrating the boundaries of the claimed design and form no part of the claimed design.

1 Claim, 7 Drawing Sheets
